ALKYLATION OF AROMATIC COMPOUNDS

Louis Schmerling, Chicago, Ill., assignor to Universal Oil Products Company, Chicago, Ill., a corporation of Delaware

No Drawing. Application September 28, 1942,
Serial No. 459,949

5 Claims. (Cl. 260—671)

This is a continuation-in-part of my co-pending application Serial No. 399,688, filed June 25, 1941.

This invention relates to the production of alkyl derivatives of aromatic compounds. It is more particularly concerned with a novel method for effecting the alkylation of aromatic hydrocarbons with olefinic hydrocarbons or olefin-producing substances.

In one specific embodiment the present invention comprises a process for producing alkylated aromatic hydrocarbons which comprises reacting an aromatic hydrocarbon with an olefinic hydrocarbon under alkylation conditions in the presence of a solution formed by adding an aluminum halide and a catalytically inert salt to a nitroparaffin.

Mono nuclear aromatic hydrocarbons such as benzene, toluene, and other alkylated benzenes as well as the poly nuclear aromatics including naphthalene and the alkylated naphthalenes may be alkylated in accordance with the present process as hereinafter described in greater detail. These aromatic hydrocarbons are readily available as by-products in the coal tar industry and they may be obtained by the dehydrogenation of naphthalic hydrocarbons, by the dehydrogenation and cyclization of aliphatic hydrocarbons and by other means.

Either normally gaseous or normally liquid olefins including ethylene, propylene, butylenes and the higher homologues thereof may be employed as alkylation agents. Polymers, di-olefins, cyclic olefins and other poly olefins may also be reacted with aromatic hydrocarbons but not necessarily under the same conditions of operation which may be employed when aromatic hydrocarbons are alkylated with the straight-chain and branched chain olefins. The aliphatic olefins are generally available from the catalytic or thermal cracking of hydrocarbon oils and also from various other hydrocarbon conversion reactions. In certain cases various olefin-producing substances such as alcohols, ethers, esters, alkyl halides, etc. may be utilized as alkylation agents to produce alkyl aromatics, although again the olefin-producing substances are not to be considered as being on an equivalent basis with other alkylation agents since somewhat different operating conditions may be necessary.

A solution formed by adding an aluminum halide such as aluminum chloride, aluminum bromide or mixtures thereof to a nitro-paraffin

such as nitromethane, nitroethane, 1-nitropropane, 2-nitropropane or a nitroparaffin of higher molecular weight is an effective catalyst for the alkylation of aromatic hydrocarbons with the various alkylation agents hereinbefore described. Under ordinary alkylation conditions of temperature and pressure such solutions of aluminum chloride are frequently miscible with the aromatic hydrocarbon, e. g., benzene, which is undergoing alkylation. In a certain sense the nitroparaffin may thus be said to serve as a solutizer for distributing the aluminum chloride in the aromatic hydrocarbon phase. Thus if one part by weight of aluminum chloride is dissolved in an equal weight of nitromethane and the solution is added to benzene, a clear yellow solution results when either 1 or 100 parts by weight of benzene are used. Accordingly, a homogeneous catalytic reaction may be carried out by introducing an alkylation agent into the solution under appropriate conditions.

While the catalytic alkylation of aromatics in a homogeneous system has obvious advantages because of the intimacy of contact between the catalyst and reactants and is of considerable theoretical interest, in most cases it has the practical disadvantage that recycling of the catalyst is not possible since it is dissolved in the single phase product. I have now found that this disadvantage may be overcome to a large extent by employing as a catalyst a solution formed by adding a substantially catalytically inert salt as well as the aluminum halide to a nitroparaffin. In general, I prefer to employ the alkali and alkaline earth halides, particularly the chlorides and bromides. The presence of these catalytically inert salts in sufficient amounts minimizes or in many cases prevents the solution of the catalyst in the benzene or other aromatic. For example, 5 parts by weight of aluminum chloride may be added to 11.3 parts by weight of nitromethane along with 2.2 parts by weight of sodium chloride. A clear yellow solution is obtained which when added to 80 parts by weight of benzene causes the separation of a deep red lower layer. It is apparent that the presence of sodium chloride serves to "salt out" the catalyst solution. In general, the alkali and alkaline earth chlorides and bromides are insoluble in the nitroparaffins but are quite soluble in nitroparaffin solutions of aluminum halides, particularly aluminum chloride.

The different nitroparaffins which may be used for forming the catalyst solutions of the present

invention do not necessarily produce catalysts which are equivalent in their activity. The particular nitroparaffin chosen will be dependent upon the nature and proportions of the hydrocarbons being reacted, the conditions of operation, and other factors. The molar ratio of catalytically inert salt to aluminum halide which may be employed may vary from about 0.1 to about 1.5 or somewhat higher, dependent upon the solubility. In many cases I prefer to have approximately equimolar proportions of the catalytically inert salt and the aluminum halide. For example, in the case of sodium chloride, slightly less than 1 mol of the sodium salt dissolves in the nitroparaffin for each mol of aluminum chloride present.

When aluminum chloride, in the form of a granular solid material, is employed as a catalyst for the alkylation of aromatic hydrocarbons with olefinic hydrocarbons, the formation of sludge-like material upon the surface of the aluminum chloride during use decreases its catalytic activity and ordinarily makes it necessary to withdraw the sludge-like material and replace it with additional quantities of fresh catalyst. A distinct advantage, however, of the present catalyst which may comprise, for example, nitromethane containing aluminum chloride and sodium chloride, is that only very small quantities of the aromatic reactant are converted to the sludge-like material or "lower layer." Therefore, appreciably higher yields are obtained and the catalyst life is longer. Furthermore, since the catalysts of the present invention are immiscible to a large extent with the hydrocarbon reactants, a separation may readily be effected between the hydrocarbon reaction products and the used catalyst. Thus, the catalyst may be employed in either a batch or continuous system by methods well-known to those skilled in the art of alkylating hydrocarbons, using a liquid alkylation catalyst.

In a continuous process, the alkylation treatment is effected by subjecting the aromatic reactant and the catalyst solution to intimate contact by means of an agitating device and charging controlled amounts of the olefinic reactants or other alkylating agent to the reaction zone. The reaction mixture is allowed to settle into an upper hydrocarbon layer which is fractionated for the recovery of desired products of the reaction and unconverted reactants which are recycled to the alkylation zone while a lower used catalyst layer is also withdrawn and may be recycled to the alkylation zone if desired. A portion of the spent catalyst may be continuously or intermittently withdrawn from the system and subjected to hydrolysis for the removal of remaining amounts of aluminum chloride and the nitroparaffins may be separated from the residual mixture by fractional distillation, by extraction or by hydrolysis with a mineral acid. The recovered nitroparaffin may be recycled to further use in the process.

The alkylation of an aromatic hydrocarbon by an olefinic hydrocarbon, in accordance with the present invention, is preferably carried out at a temperature of from about -10 to about 100° C. and under a pressure of from substantially atmospheric to about 100 atmospheres. The particular temperature employed in any given alkylation reaction will depend upon the properties of the aromatic hydrocarbon undergoing alkylation. In the alkylation zone, it is preferable to have a substantial excess of aromatic hydrocar-

bons present at all times in order to retard competing side reactions such as polymerization of the olefinic reactants. In general, the molar ratio of aromatic to olefinic hydrocarbon should be from about 3:1 to about 40:1 or higher. A relatively small amount of hydrogen halide, particularly hydrogen chloride, may be introduced into the alkylation zone in order to promote the activity of the catalyst. Generally, the amount of hydrogen halide present will not exceed more than about 5% by weight of the total hydrocarbon mixture. It is frequently desirable to have hydrogen present generally in a quantity of not more than about 10 mol per cent of the total hydrocarbons charged.

The following experimental data are introduced in order to illustrate the nature of the results which may be obtained according to the present invention. However, it is not intended that the scope of the invention be limited unduly.

EXAMPLE I

A catalyst solution was prepared by adding 5 parts by weight aluminum chloride to 10 parts by weight of nitromethane and then adding 2.2 parts by weight of sodium chloride. At room temperature and pressure all but about 0.3 to 0.5 part by weight of the sodium chloride dissolved in the nitromethane and aluminum chloride yielding a clear yellow solution. This catalyst was employed in a series of 3 runs in which benzene was alkylated with propylene and with isopropyl chloride. The pertinent data from these runs are tabulated in the following table.

Table

	Run		
	A	B	C
Reactants, gms.:			
Benzene.....	80	80	80
Propylene.....	20	21	0
Isopropyl chloride.....	0	0	40
Hydrogen chloride.....	0	2.5	0
Catalyst.....	17	17	17
Pressure, atm.:			
Initial (N ₂).....	30	30	30
Maximum.....	40	38	35
Final (at room temp.).....	34	30	35
Temp., °C.....	60	60	60
Duration, hrs.....	4	4	4
Products, gms.:			
Condensable at -78°C.....	6	0	0
Upper layer.....	88	103	106
Catalyst layer.....	12	15	15
Hydrogen chloride.....	1	—	13
Loss.....	11	0	4
Distillation of upper layer, vol. percent:			
IBP-40°C.....			
40-70.....	79	54	51
70-85.....	2	1	2
95-150.....	8	30	26
150-175.....	9	9	2
175-200.....	6	5	12

The experiments were conducted as batch experiments employing a glass lined rotating autoclave of the Ipatieff type. An initial pressure of 30 atmospheres was maintained in each case by the introduction of nitrogen. It will be apparent by comparing runs A and B that the presence of hydrogen chloride resulted in a substantial increase in the production of mono-isopropyl benzene as evidenced by the volume per cent of the

150-175° C. fraction recovered from the reaction products.

EXAMPLE II

A solution was prepared by adding 5 parts by weight of aluminum chloride to 11.3 parts by weight of nitromethane and 82.4 parts by weight

of benzene. A homogeneous red solution resulted. A series of catalysts was then prepared by adding 0.05 part by weight of the following alkali and alkaline earth halides to portions of this solution: sodium chloride, potassium chloride, calcium chloride, sodium bromide and potassium bromide. In each case "salting out" of the catalyst layer occurred. The mixture of catalyst layer and benzene layer was then commingled with isopropyl chloride and the entire mixture was agitated in each case at room temperature and atmospheric pressure. Substantial yields of isopropyl benzene were obtained with each catalyst.

I claim as my invention:

1. An alkylation process which comprises reacting an aromatic hydrocarbon with an alkylating agent under alkylating conditions in intimate contact with a solution of an aluminum halide catalyst in a nitroparaffin and containing a relatively inert salt selected from the group consisting of the alkali and alkaline earth metal chlorides and bromides, said salt being in sufficient amount to render the catalyst solution immiscible with said aromatic hydrocarbon, thereafter separating the reaction mixture by stratification into a hydrocarbon layer and a catalyst layer comprising said solution, and recycling at

least a portion of said catalyst layer to the alkylating step.

2. An alkylation process which comprises reacting an aromatic hydrocarbon with an olefinic hydrocarbon under alkylating conditions in intimate contact with a solution of an aluminum chloride catalyst in a nitroparaffin and containing a relatively inert salt selected from the group consisting of the alkali and alkaline earth metal chlorides and bromides, said salt being in sufficient amount to render the catalyst solution immiscible with said aromatic hydrocarbon, thereafter separating the reaction mixture by stratification into a hydrocarbon layer and a catalyst layer comprising said solution, and recycling at

15 least a portion of said catalyst layer to the alkylating step.

3. The process as defined in claim 2 further characterized in that said salt is sodium chloride.

20 4. The process as defined in claim 2 further characterized in that said nitroparaffin is nitro-methane.

25 5. The process as defined in claim 2 further characterized in that said aromatic hydrocarbon is benzene.

LOUIS SCHMERLING.
